UNITED STATES PATENT OFFICE.

FRANK DE CAUSSE, OF NEW YORK, N. Y., ASSIGNOR TO H. H. FRANKLIN MANUFACTURING COMPANY, OF SYRACUSE, NEW YORK, A CORPORATION OF NEW YORK.

DESIGN FOR AN AUTOMOBILE RADIATOR OR THE LIKE.

Application filed March 17, 1925. Serial No. 12,751. Term of patent 3½ years.

To all whom it may concern:

Be it known that I, FRANK DE CAUSSE, a citizen of the United States, residing at New York city, in the county of New York, borough of Manhattan, and State of New York, and having his post-office address at 4 West 53rd Street, New York city, have invented a new, original, and ornamental Design for an Automobile Radiator or the like, of which the following is a specification, reference being had to the accompanying drawing, forming part thereof.

In the drawing, the figure is a perspective view of an automobile embodying my new design.

I claim:

The ornamental design for an automobile radiator or the like substantially as shown.

In testimony whereof, I have hereunto signed my name, at Syracuse, in the county of Onondaga, and State of New York, this 6th day of March, 1925.

FRANK DE CAUSSE.
